UNITED STATES PATENT OFFICE

172,298

APPAREL CLOSURE

Henning af Odencrants, Sharon, Conn., assignor to North & Judd Manufacturing Company, New Britain, Conn., a corporation of Connecticut

Application February 4, 1954, Serial No. 28,831

Term of patent 3½ years

(Cl. D17—3)

To all whom it may concern:

Be it known that I, Henning af Odencrants, a citizen of the United States and a resident of Sharon, in the county of Litchfield, State of Connecticut, have invented a new, original, and ornamental Design for an Apparel Closure, of which the following is a specification, reference being had to the accompanying drawing, forming part hereof.

In the accompanying drawing:

I claim:

The ornamental design for an apparel closure, as shown.
